(57) CLAIM

The ornamental design for a sandwich decruster, as shown and described.

DESCRIPTION

FIG. 1 is a top perspective view of the sandwich decruster of the present invention;

FIG. 2 is a bottom perspective view thereof;

FIG. 3 is a side elevational view thereof;

FIG. 4 is a top plan view thereof;

FIG. 5 is a bottom plan view thereof;

FIG. 6 is a top perspective view of an alternate embodiment of FIG. 1;

FIG. 7 is a bottom perspective view of FIG. 6;

FIG. 8 is a side elevational view of FIG. 6;

FIG. 9 is a top plan view thereof; and,

FIG. 10 is a bottom plan view thereof.

The broken lines are for illustrative purposes only and form no part of the claimed design.
